UNITED STATES PATENT OFFICE

ARTHUR E. MANHEIMER, OF CHICAGO, ILLINOIS, ASSIGNOR TO MANHEIMER WATCH COMPANY, OF CHICAGO, ILLINOIS, A CORPORATION OF ILLINOIS

WRIST WATCH

Application filed May 21, 1928. Serial No. 279,386.

This invention relates to improvements in wrist watches and the like, of the type commonly secured to the wrist, ankle, or other appropriate portion of the body of a wearer, by means of a bracelet or the like, formed of metal, leather, or any desirable material. The invention relates more particularly to improved means for attaching a bracelet to the case of a watch of this character.

10 In the past, many and varied means have been employed for the securement of a bracelet, strap, or band to a watch case, and though these means have been effective in holding the respective parts properly united, yet they have proven objectionable, in most instances, due to the fact that they detracted materially from the appearance of the combined watch and bracelet. Heretofore, it has been common practice to provide lugs projecting from the watch case in an unsightly manner, to which the ends of the bracelet are secured, or provide other means engageable with a watch case and bracelet, but in each instance the bracelet ends and substantially all of the securing means are plainly visible, thereby detracting from the general appearance of the watch. Moreover, with these formerly known means it was frequently undesirably difficult to properly attach a bracelet to a watch case. Further, these means were so exposed that they frequently became entangled with the apparel of a wearer, and maintained the bracelet ends in such a position of exposure that they not infrequently were prematurely worn out.

15 The present invention is designed to overcome the above noted defects and objections in the provision of means for securing a bracelet to a watch case in such a manner that the bracelet ends are shielded and protected and the securing means are substantially invisible.

The present invention also seeks to provide means for attaching a bracelet to a watch case so as to give a resulting appearance as though the bracelet passed entirely through the watch case itself, the securing means being substantially invisible.

20 A further object of the present invention is to provide means for easily and readily

attaching a bracelet to a watch case with no resulting injury to the bracelet or case.

A still further object of the present invention is to provide means for attaching a bracelet to a watch case, in such a manner, 55 that the exposed portions of the means form substantially a part of the case itself and may be embellished or engraved to conform with the figuring on the case.

A still further object of the present invention is to provide means for attaching a bracelet to a watch case, which means eliminate the need of any parts whatsoever projecting from the watch case.

While some of the more salient features, 60 characteristics, and advantages, of the means embodying the present invention have been above pointed out, others will become apparent from the following disclosures.

The invention includes these and other 65 features of construction and combinations of parts hereinafter described, and shown in a preferred form in the drawing, as more particularly indicated by the claims.

On the drawing:

Figure 1 is a fragmentary plan view of a 70 watch with a bracelet attached thereto by means embodying the principles of the present invention.

Figure 2 is an enlarged fragmentary side 75 view of a portion of the structure shown in Figure 1, taken substantially as indicated by the line II-II of Figure 1.

Figure 3 is an enlarged fragmentary plan 80 sectional view, with parts in elevation, taken along the line III-III of Figure 2.

Figure 4 is a fragmentary sectional view 85 taken substantially as indicated by line IV-IV of Figure 3.

Figure 5 is a view similar to Figure 4, 90 taken substantially along line V-V of Figure 3.

Figure 6 is an enlarged sectional view, 95 with parts in elevation, taken substantially along line VI-VI of Figure 1.

Figure 7 is a view similar to Figure 3, 100 showing a slightly different form of the present invention.

Figure 8 is a fragmentary sectional view

taken substantially along line VIII—VIII of Figure 7.

As shown in the drawing:

The structure selected to adequately disclose the illustrated embodiment of the present invention includes a watch 1 embodying a case 2 including the customary back cover 3 and front cover or bezel 4, and a two-piece strap 5 which is secured to the watch case by improved means as will later appear. At the outset, it is to be clearly understood that although a leather strap is shown to illustrate a preferred form of the invention, the invention is equally adaptable for the attachment of any form of bracelet or metallic band to the watch case 2, and herein and in the appended claims the term "strap" and the showing thereof in the drawing is to be construed as being of any desirable material.

Since both ends of the strap 5 are secured to the watch case in identical manner, the construction centered around one end only will be described herein. The body part of the watch case 2 is provided, in this instance, with a transversely extending key hole slot 6 adjacent each end thereof, the restricted throat of the slot being disposed outwardly. The inner ends of the strap 5 are each provided with an integral loop 7 which loops are slideable within the slots 6, the strap proper adjacent the loops substantially filling the restricted throats of the slots, thereby giving the appearance, as clearly shown in Figures 1 and 2, of the strap passing entirely through the watch case itself.

It is to be noted that the loop 7 on an end of the strap 5, is entirely sufficient to retain the strap in positive engagement with the watch case, and, especially when a metal bracelet is used, no further securing means are necessary with the single exception of means to prevent longitudinal movement of the loop. However, when the strap is made of extremely fine leather, fabric, or similar material, it has been found desirable to somewhat reinforce the loop so as to eliminate excessive wear thereon, and, in the present instance, this is accomplished by the passing of a pin 8 through the loop, the inner end of the pin resting in a reduced recess 9 at the termination of the key hole slot 6. Since the key hole slot 6 terminates a distance from the opposite side of the case 2, the pin 8 is provided with a head 10 of a diameter substantially that of the loop 7 and of a length equal to the aforesaid distance, for the purpose of properly centering the strap with respect to the side edges of the case. The head 10 slides into the key hole slot 6 so that the end thereof is flush with the casing edge as shown more clearly in Figures 2 and 3, and this end may be embossed or engraved to correspond with the figuring on the case.

A tongue-like portion 11 is formed integral with the head 10 and extends within the re-

stricted throat of the key hole slot, the outer edge of the tongue 11, of course, being finished in conformity with the respective edge of the casing. The head 10 is notched, as at 12, to provide a shoulder 13 which is engaged by the bezel 4 of the case 2, this engagement preventing rotative or longitudinal movement of the head 10 and pin 8, whereby the strap is positively secured to the watch case.

To separate the strap from the case it is simply necessary to remove the bezel 4, grip the strap adjacent the case and slide the same transversely, the loop carrying the pin therewith as it leaves the key hole slot. The preferred form of connecting the strap to the case is to previously insert the pin into the loop, simultaneously slide both elements into the key hole slot, and snap the bezel into place.

It will be apparent from the foregoing, that the only portions of the securing means which are visible, are the outer edge of the tongue 11 and the top of the head 10, but these portions being finished in accordance with the watch case itself which gives the resulting effect of invisibility to the securing means.

In Figures 7 and 8, I have shown a slightly different form of construction which is especially adaptable for use with a metal bracelet. In some instances, it may prove more economical to provide a metal bracelet with a solid cylindrical portion 14 integral therewith, rather than with a loop. With this structure, or as hereinbefore stated, with a fairly rigid loop, the pin 8 is not essential. However, to provide a finished appearance and to properly center the strap, a plug 15 is utilized when the pin is omitted, the plug 15 corresponding, in all respects, to the head 10 of the pin which was previously described herein.

It is to be noted that in the event a watch is to be worn as a pendant or the like, a sautoir or similar suspension may be joined with the watch case in the manner previously described herein for a strap.

From the foregoing, it is apparent that I have provided novel and easily operable means for securing a strap, bracelet, band, or similar attachment device, to a watch case, wherein the means and strap ends are effectively concealed and protected, leaving no projecting parts to detract from the general appearance of the watch and bracelet. Moreover, the means disclosed herein are positive in their action, durable, and may be economically manufactured.

I am aware that many changes may be made and numerous details of construction may be varied through a wide range without departing from the principles of this invention and I, therefore, do not purpose limiting the patent granted hereon otherwise than necessitated by the prior art.

I claim as my invention:

1. In combination, a watch case including a bezel, said case having slots in opposed edges thereof for receiving the ends of a strap, and means engageable in said slots for retaining said ends therein, said bezel engaging said means to prevent movement of the latter. 5
2. In combination, a watch case including a cover and having a pair of opposed slots therein, a strap for said case and having means for securing said strap to said case by engagement in said slots, and means engageable by the cover of said case for maintaining said strap in centralized position with respect to said case. 10
3. In combination, a watch case including a cover and having a constricted slot adjacent each of a pair of opposed edges thereof, a pair of strap segments, each segment having a loop on an end thereof, a pin for insertion in each of said loops, each of said loops with the pin therein being insertable simultaneously in one of said slots, and an enlarged head on each of said pins provided with a shoulder engageable by the cover of said case. 15
4. In a device of the class described, a watch including a body, a cover therefor, said body having a slot, a strap having a portion disposed in said slot, means for preventing removal of said portion from said slot, said means being engageable with the inside portion of said cover, whereby the latter prevents removal of said means. 20
5. In a device of the class described, a watch body having a recess, a strap having one end in said recess, a cover for said body and having a portion projecting into said recess, and means for preventing removal of said strap, said means being disposed in said recess and between the strap and the projecting portion, whereby said portion prevents removal of said means. 25
6. In a device of the class described, a watch body having a recess, a strap having one end in said recess, a cover on the body, and means interlocked with said strap to prevent withdrawal thereof, said means being also interlocked with said cover, whereby the latter prevents undesired removal of said means. 30
7. In a device of the class described, a watch body having a recess, a strap having an end in said recess, a cover on said body and restricting said recess, and means for preventing withdrawal of the strap, said means occupying unrestricted and restricted portions of said recess, whereby withdrawal of said means is prevented. 35
8. In a device of the class described, a body having a recess provided with an open end, a strap having an end insertable through said open end into said recess, means for preventing removal of said strap end from 40
- said recess, said means comprising a plug having an outer rabbeted portion, and a cover for said body, said cover projecting into said rabbeted portion to prevent removal of the plug. 70
9. In a device of the class described, a body having a recess open along one side and an end, said side being restricted, a strap having an enlarged end in said recess, and a cover on said body and projecting into the open end of said recess to prevent removal of the strap end therefrom. 75
10. In a device of the class described, a watch body, a cover therefor, said body having a recess open at one end, a strap having an end disposed in said recess, and means to prevent withdrawal of said strap end from said recess, said means comprising a plug insertable into the open end of said recess and provided with an outwardly facing shoulder, said cover being engaged with said shoulder to prevent removal of the plug, said body and plug including means to facilitate the positioning of said plug for engagement of its shoulder by said cover. 80
11. In a device of the class described, a watch body having a longitudinal slot provided with a constricted throat, a fastener for said watch, said fastener fitting in said throat and having an end disposed in said slot and of greater transverse dimension than said throat, whereby said body and fastener are interlocked, and means removably carried by said body for maintaining said body and fastener against undesired separation. 85
12. In a device of the class described, a watch body having a longitudinal slot provided with a constricted throat, a fastener for said watch, said fastener fitting in said throat and having an end disposed in said slot and of greater transverse dimension than said throat, and means including a portion spaced from the wall of said slot by said end for maintaining said body and fastener against undesired separation. 90
13. In a device of the class described, a watch body having a slot provided with a constricted throat, a strap doubled over itself, and means intermediate the inner extremity of the bight and said throat for preventing removal of said bight through said throat. 95
14. In a device of the class described, a watch body having a slot provided with a constricted throat, a strap doubled over itself, and means intermediate the inner extremity of the bight and said throat for preventing removal of said bight through said throat, said throat constituting means with respect to which said strap may be flexed. 100
15. In a device of the class described, a watch body having a slot provided with a constricted throat, a strap doubled over itself, and means intermediate the inner extremity of the bight and said throat for preventing removal of said bight through said throat, 105
- 110
- 115
- 120
- 125
- 130

said means comprising a pin for maintaining the portions of the strap adjacent the bight in spaced relationship.

16. In a device of the class described, a watch body having a slot provided with a constricted throat, a strap doubled over itself, and means for enlarging said bight to prevent removal of said bight through said throat.

10 17. In a device of the class described, a watch body having a slot provided with a constricted throat, a strap having an end in the form of a loop disposed in and completely concealed by said body adjacent said slot, and 15 means for preventing withdrawal of the loop through said throat.

18. In a device of the class described, a watch body having a slot provided with a constricted throat, a strap having an end doubled upon itself and removable from the slot through said throat, and means for enlarging said end to prevent its removal from the slot through said throat, said body completely concealing the end thus enlarged.

20 25. In testimony whereof, I have hereunto subscribed my name at Chicago, Cook County, Illinois.

ARTHUR E. MANHEIMER.
